US00D950740S

(12) **United States Design Patent** (10) Patent No.: **US D950,740 S**
(45) Date of Patent: ** May 3, 2022

(54) **ADHESIVE BANDAGE WITH DECORATED PAD**

(71) Applicant: **Johnson & Johnson Consumer Inc.**, Skillman, NJ (US)

(72) Inventors: **Leonardo Caneppele**, Jacareí (BR); **Paulo Cesar de Godoy Oriani**, Itatiba (BR); **Melinda Cettina**, Skillman, NJ (US)

(73) Assignee: **Johnson & Johnson Consumer Inc.**, Skillman, NJ (US)

(**) Term: **15 Years**

(21) Appl. No.: **29/725,578**

(22) Filed: **Feb. 26, 2020**

Related U.S. Application Data

(62) Division of application No. 29/654,731, filed on Jun. 27, 2018, now Pat. No. Des. 887,564.

Primary Examiner — Darcey E Gottschalk

CLAIM

We claim the ornamental design for an adhesive bandage with decorated pad, as shown and described.

DESCRIPTION

FIG. 1 is a top perspective view of the present invention; FIG. 2 is a top view of the adhesive bandage with decorated pad depicted in FIG. 1;

FIG. 3 is a left side view of the adhesive bandage with decorated pad depicted in FIG. 1;

FIG. 4 is a bottom view of the adhesive bandage with decorated pad depicted in FIG. 1;

FIG. 5 is a right side view of the adhesive bandage with decorated pad depicted in FIG. 1;

FIG. 6 is a front side view of the adhesive bandage with decorated pad depicted in FIG. 1; and,

FIG. 7 is a back side view of the adhesive bandage with decorated pad depicted in FIG. 1.

The ornamental design which is claimed is shown in solid lines in the drawings.
